SELF-PROPELLED TOY SUBMARINE

Frederick Sabini, Salem, N. J.

Application June 4, 1946, Serial No. 674,165

9 Claims. (Cl. 46—94)

1

This invention relates to improvements in toys; and the invention has reference, more particularly, to a novel construction of self-propelled toy submarine.

The invention has for an object to provide a novel construction of self-propelled and self-submerging toy submarine adapted to propel itself for an appreciable period of time on the surface of water and then, while still propelling itself, to automatically submerge below said water surface.

The invention has for another object to provide a toy submarine, characterized as above stated, comprising a hollow body or hull within the interior of which is rotatably mounted a water wheel, the latter being affixed to and being adapted to drive a propeller shaft arranged to extent exteriorly from the stern end of the hull, and to the exterior end of which shaft is fixed a propeller; said hull being provided, below its normal waterline, with water admission means adapted to lead in-flowing water into actuating contact with said water wheel.

The invention has for a further object to provide within the hull of a toy submarine, characterized as above stated, a suitably located air chamber means wherein air may be trapped to provide the hull with sufficient buoyancy to float the same when submerged; said air chamber having selectively usable air venting means, selective use of which renders said buoying air chamber operative or inoperative at will.

Another object of the invention is to provide a transverse partition within the interior of the toy submarine hull, and of less height than said interior, which is spaced forwardly of the stern end of said hull, whereby to provide support for the water wheel and propeller shaft, and which, at the same time, is adapted to form a temporary air chamber in the stern end of the hull for temporarily buoying said hull stern during submerging movement of the hull, whereby to cause said hull to dive bow foremost when submerging.

Other objects of the invention, not at this time more particularly enumerated, will be understood from the following detailed description of the same.

An illustrative embodiment of the invention is shown in the accompanying drawings, in which—

Fig. 1 is a side elevational view of the self-propelled toy submarine according to this invention, showing the same in initial position afloat upon the surface of water; Fig. 2 is a bow end elevational view of the same; Fig. 3 is a longitudinal sectional view of the same, taken on line 3—3

2

in Fig. 2; and Fig. 4 is a cross sectional view of the same, taken on line 4—4 in Fig. 3.

Fig. 5 is a longitudinal sectional view similar to that of Fig. 3, but showing the toy submarine in the act of submerging; and Fig. 6 is a similar view, showing the toy submarine in submerged position.

Similar characters of reference are employed in the above described views to indicate corresponding parts.

Referring to the drawings, the novel self-propelled and self-submerging toy submarine according to this invention comprises a hollow body or hull formed by a bottom portion 10, side portions 11 and top or deck portion 12; said body or hull being suitable shaped to simulate the appearance of a submarine. Said body or hull may be made of any suitable material, such e. g. as sheet metal, plastic material, wood, etc. Joined to and rising from the top or deck portion 12 of the hull is a hollow body extension 13, which may be suitably shaped to simulate the conning tower of a submarine. Said hollow body extension 13 is open at its bottom so as to communicate with the interior of the hull, and its interior provides an air trapping chamber 14 for purposes hereinafter disclosed. Extending perpendicularly through the interior of the air trapping chamber 14 and thence through the top of the body extension 13, so as to project exteriorly from the latter in upstanding relation thereto is a tubular periscope simulating member 15, which is adapted to provide an endwise open air vent passage 16, the lower end of which terminates at the approximate open bottom level of said air trapping chamber 14. Formed in connection with the top of the body section 13 is a tubular exteriorly projecting neck 17, the passage of which provides a second vent 18 leading outwardly from the top level of said air trapping chamber 14. Means is provided for closing either one of said air vent passages 16 or 18 when the other thereof is desired to be left open for air venting service, whereby said air vent passages are subject to optional use accordingly as it may be desired to have the hull float at a submerged level after driving, or to sink to the bottom after diving; as well be hereinafter further explained. To this end, a closure cap 19 is provided, subject to selective application to either the external open end of the periscope 15 or the external open end of the neck 17. Said closure cap 19 is preferably tethered to the hull by a flexible tether, such e. g. as a length of chain 20, whereby said closure cap is safeguarded against loss, and yet freely

50 55

selectively transferable from one vent means to the other. Any other suitable means for closing and opening the air vent passages may be provided.

Suitably located within the interior of the hull, in affixed relation to the bottom portion 10 thereof, is a weight member 21 to ballast the hull and to assure its riding on an even keel, and also to aid bow end gravitation of the hull during its diving movement when submerging.

Provided within the stern end portion of the hull interior, in forwardly spaced relation to the stern end wall 22 of the hull, is a transverse partition 23 which rises from the hull bottom portion 10 but terminates short of the hull deck portion 12, so as to provide a spill over opening or passage 24 to afford communication between the forward interior part 25 and the rearward interior part 26 intermediate said partition 23 and the stern end wall 22. Said rearward interior part 26 provides a temporary air trapping chamber in the stern of the hull for temporarily buoying the stern during submerging of the hull, whereby to cause the latter to dive bow foremost when submerging, as will be hereinafter more fully explained.

Suitably formed and located in connection with said partition 23 is an intersecting bearing sleeve 27, and, in like manner, suitably formed and located in connection with the stern end wall 22 is a bearing sleeve 28, which is disposed in axial alignment with the bearing sleeve 27. Journaled in and between said bearing sleeves 27 and 28 is a propeller shaft 29, the rearward end of which projects exteriorly of said stern end wall 22 at a point below the normal initial waterline of the hull. Fixed on the exterior end of said propeller shaft 29 is a propeller member 30. Fixed on the forward end of said propeller shaft 29, which projects through and forwardly from the partition 23, is a water wheel 31, by which the propeller shaft and its propeller member is driven.

Connected with a side portion 11 of the hull is an outwardly open water admission means, the water intake end of which is located below the normal waterline of the hull, and the inner discharge end of which is directed toward the vanes of the water wheel 31. Said water admission means may be constructed and formed in any suitable manner, so long as it will function to admit in-flow of water from the exterior of the hull to the interior thereof, and to direct the in-flowing water stream against the water wheel, whereby to actuate the latter. A preferable form and construction of the water admission means, as shown, comprises a water intake conduit 32, having an outer end opening through the wall of a side portion 11 of the hull, so as to provide a water admission port 33 therein. The inner or discharge end of said conduit 32 extends to the periphery of the water wheel 31, preferably to the underside of the latter, whereby to actuate the same by an undershot mode of operation. Preferably, the inner discharge end of said conduit 32 terminates in a water guide chute or trough 34 which embraces a portion of the water wheel periphery, whereby to better direct and apply the in-flowing water stream in operative engagement with the water wheel vanes. If desired, the water admission port 33 may be covered by a forwardly open scoop-like guard 35, which is suitably affixed to the exterior face of the hull side portion 11 wherein said water admission port is located. This scoop-like guard 35 serves to prevent a child, when playing with the toy, from inserting anything into or through the water admission means

which might either block or choke the same, or do injury to the water wheel; and said scoop-like guard is also adapted to serve the additional purpose of scooping up the water and directing the same into the water admission means as the hull moves forwardly through the water, thereby to accelerate in-flow of water, and thus increase the power of its operative thrust upon the water wheel.

10 Affixed to the stern end wall 22 of the hull, to extend therefrom beneath and partially around the propeller member 30 is a propeller guard 36, adapted to shield the same from being knocked or struck with possible risk of injury thereto.

15 In the use and operation of the toy submarine of this invention, the hull, being empty, is set afloat upon the surface of water. In such initial floating position of the hull, the water admission port 33 is submerged just below the water surface and waterline level of the hull. Immediately the

20 hull is thus set afloat, water will pass inwardly through the admission port 33 and intake conduit 32, thus establishing an inflowing water stream which is directed against the vanes of the water wheel 31, so that the impact and thrust thereof upon the latter imparts operative rotative movement thereto. The revolution of the water wheel rotates the propeller shaft 29 and propeller member 30.

25 Revolution of the propeller member 30 effects propulsion of the hull, so that the same is moved forwardly upon and through the water. The inflowing water, after spending its force upon the water wheel, discharges into the forward interior part 25 of the hull, and gradually accumulates therein, so that the weight thereof gradually

30 bears the bow end of the hull downward, thus causing said hull to incline downwardly and thereby assume diving position. Such downward inclination of the hull into diving attitude is further assisted and assured by the air which is trapped in the temporary air trapping chamber 26, which acts to buoy up the stern end of the hull (see Fig. 5). In the meantime, inflowing water continues to actuate the water wheel and the propeller member operated thereby, so that

35 forward propulsion of the hull continues. As the water level rises in the forward interior part 25 of the hull, the air displaced thereby is vented through either the periscope air vent passage 16 or the second air vent passage 18, whichever is left open.

40 The described operation of the toy submarine continues until the water level within the interior part 25 of the hull reaches the top margin of the partition 23. When this occurs, the water spills over said partition through the spill over opening or passage 24 into the temporary air trapping chamber 26, so as to displace the air from the latter, whereupon the stern end of the hull is weighed down, and the hull assumes a substantially even keel submerged position.

45 If the second air vent 18 is closed by the closure cap 19, the air escapes from the hull interior through the periscope air vent passage 16. This continues until the water level within the hull

50 interior rises to the bottom of the air trapping chamber 14 and the lower end of said periscope air vent passage 16, whereby to seal off the latter against further escape of air therethrough, and thus trapping air within the chamber 14, so as to provide a buoyant float adapted to buoy the submerged hull against further submersion, and so that the hull floats submerged below the water surface (see Fig. 6). Until air venting is stopped, water will continue to enter through the water

55 admission means, and the current thereof will

exert some continued but diminishing actuating thrust upon the water wheel, so that operation of the propeller member continues with forwardly propelling effect upon the hull. When air venting is arrested, inflow of water against the water wheel will cease, and forward movement of the submarine will stop as soon as the momentum thereof is overcome, whereupon the hull will lie quietly in submerged position.

If the periscope air vent passage 16 is closed by the closure cap 19, and the second air vent 18 is left open, air venting will continue until the entire interior of the hull, including the air trapping chamber 14, is filled with water. Under such circumstances, when the hull becomes full of water, the submarine will not be arrested in suspended submerged position below the water surface, but will sink to and lie upon the bottom.

In order to provide convenient means for emptying contained water from the hull interior, after operation of the toy submarine and its removal from the water, whereby to make the same ready for repetition of its operation, the hull is provided with a suitably located normally closed water discharge means. An illustrative form of such means (as shown) comprises a discharge port 37 provided in the deck portion 12 of the hull, preferably adjacent to the stern end of the latter. Said discharge port 37 is closed by an inwardly opening hinged gate or cover 38, which is yieldably urged to normal closed relation to said discharge port 37 by spring means 39. Said gate or cover 38 is preferably provided with an exteriorly projecting manipulatable push-piece 40, by means of which it may be swung to open relation to said discharge port 37. It will be obvious that, when the hull is removed from the water after use, by turning the same upside down while tilting it toward the stem thereof, and thereupon thrusting open the gate or cover 38 by actuation of the push-piece 40, the discharge port 37 will be opened to outflow therethrough the water content of the hull, so that the latter may be quickly drained and emptied ready for repeated use.

While I have described the submarine toy as adapted for both self-propulsion and self-submersion, it will be obvious that if, to provide a simple and less expensive toy, it is desired to provide the same merely for self-submersion operation without self-propulsion, this may be done by omitting the water-wheel 31, in which case, the hull will gradually assume diving position and thereafter submerge due to the inflow of water through the admission port 33 into the forward interior part of the hull until the thus admitted water overflows the partition 23 and fills the rear interior 26, whereby to complete submersion in the manner already above described.

From the above it will be readily understood that the instant invention provides a novel toy submarine of very simple and yet efficient make-up adapted for self-propulsion and self-submersion in a very realistic manner. I am aware that various changes could be made in the above described toy submarine construction without departing from the scope of this invention as defined by the following claims. It is therefore intended that all matter contained in the above description or shown in the accompanying drawings shall be interpreted as illustrative and not in a limiting sense.

I claim:

1. A self-propelling and self-submerging toy submarine comprising a hollow hull body, a ro-

tatable water wheel mounted within said hull body, a propeller means driven by said water wheel, water admission means adapted to lead water from the exterior into the interior of said hull body and into actuating contact with said water wheel, said hull body having at its top portion means to provide a chamber open toward the interior of the hull body in which air may be trapped, whereby to float the hull body at a submerged level, and said hull body having selectively usable air vent means, one adapted to vent air only from the interior of the hull body below said air trapping chamber means, and another adapted to vent air from the interior of the hull body including said air trapping chamber means.

2. A self-propelling and self-submerging toy submarine comprising a hollow hull body, a partition extending across the entire width of the interior of said hull body and forwardly spaced from its stern end, whereby to form a temporary air trapping chamber within the stern of said hull body, said partition terminating short of the top of said hull body, whereby to provide water spill over communication between the forward interior of said hull body and said temporary air trapping chamber, a rotatable water wheel disposed within said hull body at the forward side of said partition, said water wheel having a shaft extending through said partition and through the stern wall of said body, a propeller means fixed on the exterior end of said shaft, water admission means entering through a wall of the hull body at a point below the normal water-line of the latter when it is afloat on a water surface, said water admission means being adapted to lead water from the exterior into the interior of said hull body and into actuating contact with said water wheel whereby to automatically drive said propeller means, and said hull body having air vent means in its top portion.

3. A self-propelling and self-submerging toy submarine comprising a hollow hull body, a transverse partition within said hull body forwardly spaced from its stern end, whereby to provide a temporary air trapping chamber in the stern of said hull body, said partition terminating short of the top of said hull body, whereby to provide water spill over communication between the forward interior of said hull body and said temporary air trapping chamber, a rotatable water wheel mounted within said hull body at the forward side of said partition, a propeller means driven by said water wheel, water admission means adapted to lead water from the exterior into the interior of said hull body and into actuating contact with said water wheel, said hull body having at its top portion means to provide an upper air trapping chamber open toward the interior of the hull body in which air may be trapped, whereby to float the hull body at a submerged level, and said hull body having selectively usable air vent means, one adapted to vent air only from the interior of the hull body below said upper air trapping chamber means, and another adapted to vent air from the interior of the hull body including said upper air trapping chamber means.

4. A self-propelling and self-submerging toy submarine as defined in claim 2, wherein said hull body is provided with a water draining discharge port in its top portion, and a manually releasable cover plate to normally close said discharge port.

5. A self-submerging toy submarine comprising

a hollow hull body, a partition extending across the entire width of the interior of said hull body and forwardly spaced from its stern end, whereby to form a temporary air trapping chamber within the stern of said hull body, said partition terminating short of the top of said hull body, whereby to provide water spill over communication between the forward interior of said hull body and said temporary air trapping chamber, water admission means adapted to lead water from the exterior to the forward interior of said hull body, and said hull body having air vent means in its top portion.

6. A self-submerging toy submarine comprising a hollow hull body, a transverse partition within said hull body forwardly spaced from its stern end, whereby to provide a temporary air trapping chamber in the stern of said hull body, said partition terminating short of the top of said hull body, whereby to provide water spill over communication between the forward interior of said hull body and said temporary air trapping chamber, water admission means adapted to lead water from the exterior to the interior of said hull body, said hull body having at its top portion means to provide an upper air trapping chamber open toward the interior of the hull body in which air may be trapped, whereby to float said hull body at a submerged level, and said hull body having selectively usable air vent means, one adapted to vent air only from the interior of the hull body below said upper air trapping chamber means, and another adapted to vent air from the interior

5
10
15

of the hull body including said upper air trapping chamber means.

7. A self-submerging toy submarine as defined in claim 5, wherein said hull body is provided with a water draining discharge port in its top portion, and a manually releasable cover plate to normally close said discharge port.

8. A self-propelling and self-submerging toy submarine as defined in claim 1, wherein the hull body is provided with an external forwardly open scoop-shaped guard extending over the intake end of the water admission means.

9. A self-propelling and self-submerging toy submarine as defined in claim 2, wherein the hull body is provided with an external forwardly open scoop-shaped guard extending over the intake end of the water admission means.
